Inventor,
John H. Hattashmitt

UNITED STATES PATENT OFFICE.

JOHN KRUTTSCHNITT, OF SAN FRANCISCO, CALIFORNIA.

LOCOMOTIVE WHISTLE.

Application filed October 8, 1923. Serial No. 667,224.

To all whom it may concern:

Be it known that I, JOHN KRUTTSCHNITT, a citizen of the United States, residing at city and county of San Francisco and State of California, have invented certain new and useful Improvements in Locomotive Whistles, of which the following is a specification.

My invention relates to locomotive and 10 other high-pressure whistles and more particularly to means for controlling the same.

The object of my invention is to provide a locomotive whistle which can be operated and controlled instantaneously and with the 15 least possible physical labor. It is the common practice at the present time to control locomotive whistles by means of a valve opening directly against the full boiler pressure; and in order to provide the necessary 20 force to open such a valve against the full steam pressure, a system of multiplying levers and connecting links or rods is used, terminating in a cord hanging within reach of the engineer in the cab. This cord must 25 be pulled a considerable distance to open the valve, and when running on lines where the whistle must be blown at frequent intervals, the physical effort of pulling the cord is tiring and distracting to the engineer. 30 Moreover, when the engine is swaying, as when running over uneven track, the whistle cord sometimes swings to such an extent that the engineer must divert his attention from the track ahead to reach and grasp the 35 cord. The system of levers and connections commonly used is subject to wear in all its joints, necessitating frequent repairs. Moreover, such a system requires that the whistle be placed to one side of the steam dome, in 40 order that the connections may be as direct as possible, with the result that the full sound of the whistle is blown back into the cab, causing serious annoyance to the engine men.

45 By the use of the device embodying my present invention, the whistle may be placed centrally in front of the steam dome, which shields the cab from the noise, and may be controlled by a small and rigidly supported 50 lever or only a knob to be pushed with the palm of the hand, within easy reach of the engineer. Moreover, very little physical effort is necessary to operate the valve, since it is designed so that only a small part of 55 the boiler pressure keeps it shut, a slight

movement of the lever or knob being sufficient. This not only relieves the engineer of considerable labor and distraction, but also enables him to give short blasts of the whistle with greater accuracy than is the case at present.

My invention is applicable to whistles employed for a great variety of uses, but on account of its peculiar adaptability to locomotive whistles, it is so illustrated and 65 described. It is to be understood, however, that the construction may be varied from that shown and described, within the limits of the claims hereto appended, without departing from the essential principles of the 70 invention.

My invention will now be fully described with reference to the accompanying drawings, wherein—

Fig. 1 is a part sectional side elevation 75 of my improved whistle with the controlling valve therefor.

Fig. 2 is a sectional plan taken on the line 2—2 of Fig. 1.

Fig. 3 is a longitudinal section of the 80 valve operating member.

Fig. 4 is a diagrammatic plan view of the rear portion of a locomotive boiler, showing the positions of the whistle and its controlling means.

In the drawings, and referring for the moment to Fig. 1 thereof, the reference numeral 1 designates the whistle bell, which is of the usual construction. 2 is the steam pipe leading from the boiler. 3 is a valve 80 chamber member connected with the steam pipe 2 at 4, and communicating with the usual outlet at 5 to the bell 1. 6, Fig. 2, is a linearly movable valve, adapted to contact with a seat 7 formed in the member 3. Said valve 6 is fixed upon, or more preferable formed integrally with a stem 8, which carries a piston 9 operable within a cylinder 10. The valve 6 and the piston 9 are 85 acted upon, in opposite directions, by the full boiler pressure which enters the chamber 2' of the member 3 from the steam pipe 2, so that, by properly proportioning the areas of said valve and piston, as little effective pressure as may be desired may be imposed upon said valve to keep it closed. It is preferable to make the valve 6 of slightly greater area than the piston 9, so that the valve is normally held closed by the steam pressure, but can be easily opened by a com- 100 105 110

paratively slight pressure exerted upon its stem. The outer end of the cylinder 10 is closed by a cap 11, and is connected by an exterior by-pass 12 with the steam passage 12' leading from the valve to the whistle aperture 5, so that, when the valve 6 is open, the pressure is equalized on both sides of the piston 9, as well as on both sides of the valve 6.

- 10 The valve chamber member 3 carries a bracket 13, Fig. 1, having a connection at 14 for the end of a tube 15. The valve stem 8 extends through the wall of the chamber, and has a separable joint at 16, and is connected with a wire or cable 17, which is longitudinally movable within the tube 15. The diameter of the wire 17 is such that it fits freely, but without appreciable side play, within the tube 15. In practise, I prefer to 20 make the tube 15 of copper or brass and to use a stranded steel wire therein, but other materials may be used if desired.

The fixed tube 15 with its movable wire 17 is carried into the cab of the locomotive, to 25 a point within easy reach of the engineer, as indicated in Fig. 4. The end of said tube is secured by a connection 18, to a fixed barrel or guide 19 supported in any convenient manner not shown. The end of the wire 17 is fastened to a slidable plunger 20, Fig. 3, mounted within said barrel 19 and having a head or knob 21 upon its projecting end. A spring 22, positioned within the barrel 19 and acting against a collar 23 formed upon 30 the plunger 20, keeps the valve closed when there is no steam pressure in the boiler.

The whistle may be controlled by merely 35 pressing upon the knob 21, a movement of three-eighths of an inch being sufficient to fully open the valve, but for greater convenience I prefer to employ a short hand lever 24, Fig. 4, fulcrumed at 25 in an arm 26 extending from the barrel 19, and bearing against the knob 21. A stop lug 27 is 40 provided to prevent the hand lever 24 from swinging out away from the knob 21.

It will be seen that, on account of the direct connection, by means of the wire 17, between the operating lever 24 and the valve 6, 45 said valve may be very accurately and quickly controlled, to give either short or long blasts of the whistle, without any play or back-lash in the operating connections. Moreover, on account of the balanced valve construction described above, the valve is 50 easy to open, and requires but very little effort on the part of the engineer.

The whistle 1 may be placed directly in 55 front of the steam dome 28, on top of the boiler 29, as shown in Fig. 4, said dome shielding the cab 30 from the sound and steam of the whistle. The tube 15, inclosing the movable valve operating wire, may be 60 run in any convenient location into the cab 65 30, to a position within easy reach of the en-

gineer, without any additional moving parts and without appreciably increasing the friction of said wire. The operating handle 24, or the knob 21 if no handle be employed, is carried by the rigidly supported barrel 19, 70 and is therefore within reach of the engineer at all times, irrespective of any swaying or lurching of the locomotive, so that the engineer's line of vision need never be diverted in reaching for it. 75

I claim:

1. A locomotive whistle comprising a bell member; a steam connection; a valve-chamber member intervening and communicating with both the bell member and the steam connection; a valve within said chamber controlling said communication; a piston within said chamber connected with and spaced from said valve and exposed at all times to the fluid pressure of the steam connection oppositely to said pressure on the valve; a by-pass connection of the valve chamber member around said valve and piston; and means for opening said valve. 80

2. A locomotive whistle comprising a bell member; a steam connection; a valve-chamber member intervening and communicating with both the bell member and the steam connection; a valve within said chamber controlling said communication; a piston within said chamber connected with and spaced from said valve and exposed at all times to the fluid pressure of the steam connection oppositely to the pressure on the valve; a by-pass connection of the valve chamber member around said valve and piston; a stem carrying said valve and piston and projecting from the valve chamber member; a spring-controlled, linearly-movable valve-operating wire connected with 90 said stem; and a housing member for guiding said wire. 95

3. A locomotive whistle comprising a bell member; a steam connection; a valve-chamber member intervening and communicating with both the bell member and the steam connection; a valve within said chamber controlling said communication; a piston within said chamber connected with and spaced from said valve and exposed at all 100 times to the fluid pressure of the steam connection oppositely to the pressure on the valve; a by-pass connection of the valve chamber member around said valve and piston; a stem carrying said valve and piston and projecting from the valve chamber member; a linearly movable valve-operating wire connected at one end with said stem; a housing member for guiding said wire; and a spring controlled plunger connected with 110 120 the other end of said wire. 125

In testimony whereof I have signed my name to this specification.

JOHN KRUTTSCHNITT.
